[57] CLAIM

The ornamental design for a dispenser top for a pressurized container, substantially as shown.

DESCRIPTION

FIG. 1 is a perspective view of a dispenser top for a pressurized container showing my new design;
FIG. 2 is a top plan view thereof;
FIG. 3 is a rear elevational view thereof;
FIG. 4 is a side elevational view thereof;
FIG. 5 is a front elevational view thereof;
FIG. 6 is a side elevational view thereof, looking at the side opposite that shown in FIG. 4; and
FIG. 7 is a bottom plan view thereof.
